CHARLES E. GORDON, OF MARLBOROUGH, MASSACHUSETTS.

AEROHYDRO-SHIP.

1,238,907.

Specification of Letters Patent. Patented Sept. 4, 1917.

Application filed March 25, 1915. Serial No. 16,983

To all whom it may concern:

Be it known that I, CHARLES E. GORDON, a citizen of the United States, and resident of Marlborough, in the county of Middlesex 5 and State of Massachusetts, have invented certain new and useful Improvements in Aerohydro-Ships, of which the following is a specification.

The present invention relates to an apparatus 10 designed for flying and also for flotation and propulsion on water. The general objects of the invention are to provide improvements in the portion of the apparatus which supports the craft in the air, whereby increased lifting power and stability are obtained; to provide an improved 15 means for guiding and controlling the craft as to direction, elevation, and stability; to provide improved and more flexible means 20 for propelling the craft and also for applying a downward thrust on the air; to so dispose the weights on the various parts of the craft as to secure increased stability; to provide means for securing additional stability 25 when at rest upon the water or on land; to provide a novel form of boat or hull adapted to float the craft on water and to support the motors and passengers; and in general to so design the apparatus that efficiency and 30 safety may be greatly increased over air craft heretofore designed.

In the drawings which form a part of this application,

Figure 1 is a perspective view of a flying 35 ship embodying in practical form the principles of my invention and illustrating the claims appended to this specification.

Figs. 2 and 3 are respectively a plan view and an elevation of the entire ship.

40 Figs. 4, 5, and 6 are cross sections of the forward, central, and aft portions respectively of the part which I call the "superstructure" of the ship.

Figs. 7, 8, and 9 are respectively a plan 45 view, a side elevation and a front elevation of the forward end of the ship.

Figs. 10, 11, and 12 are, respectively, a plan view, a side elevation, and a front elevation of the rudder-control mechanism.

50 Figs. 13 and 14 are, respectively, a plan view and a front elevation of the hood-control mechanism.

Fig. 15 is a side elevation of one of the auxiliary pontoons and skids, with the portion 55 of the superstructure to which the same is connected.

Fig. 16 is a front view of one pair of auxiliary pontoons and skids on opposite sides of the ship with a fragment of the part of the superstructure to which they are connected. 60

The same reference characters indicate the same parts in all the figures.

My novel aerohydro-ship consists of the following principal parts or elements, to 65 wit:—a body portion 20, which I call the superstructure, and which is the part furnishing the main support for the ship when in the air; a forward rudder 21, a scoop-like forward elevator 22, wings 23, 24, and 25 at 70 the forward end of the ship, wings 26, 27, 28, and 29 at the rear end of the ship, a rigid tail piece 30, a rear rudder 31 and a boat 32.

An important feature of the invention re- 75 sides in the superstructure which is designed particularly to confine the air which is conducted to the interior thereof during propelled flight by the forward hood, to be presently described. This superstructure is 80 curved not only longitudinally but also transversely, its sides being carried downwardly and terminating in a plane considerably below the height of the longitudinal middle. The superstructure has its greatest 85 dimension longitudinally, and is of undulating outline along its longitudinal middle. Following the outline of the central longitudinal element of the superstructure as shown in Fig. 3, it will be seen that this out- 90 line first extends on a slight angle downward from the forward end, gradually curves to an upward slope, the height of which becomes greatest approximately midway between the ends, from which point the out- 95 line again curves downward to a point a short distance from the rear end, at which point there is a slight upward curve and then a short downward bend. Thus the superstructure presents a slightly upwardly 100 inclined forward end 20^a, a large hump 20^b at the middle and a small hump 20^c at the rear end, the central hump being the highest part of the superstructure. From the middle longitudinal element the surface of 105 the superstructure slopes downwardly at both sides and then outwardly, as shown by the sectional views Figs. 4, 5, and 6, the transverse curvatures at all points being of the same general character but differing in 110 degree. The cross sections are seen to be somewhat bell shaped. By virtue of this

formation, the superstructure, although being entirely open at its under side, yet partially incloses a space where air may be confined and kept under pressure somewhat greater than atmospheric when the ship is in flight. It will also be observed from the plan view, Fig. 2, as well as from the sectional views, that the superstructure has its greatest width at its middle portion and is reduced in width at both ends.

The wings briefly mentioned above are located at the forward and rear ends of the superstructure respectively and at both sides as well as in the longitudinal center thereof. 15 The wings 23 and 24 project from the opposite sides of the forward end of the superstructure and are in the same plane. The wing 25 is between the sides of the superstructure in the same plane with wings 23 and 24. All three of these wings are rigidly connected together and are angularly movable about a horizontal axis transverse to the ship. These wings are adapted to be turned about such axis to a limited extent to 20 aid in raising the craft from the land or water or in descending, and they have the further function of adding to the stability of the craft.

The wings 26, 27, and 28 are arranged 30 similarly to the wings 23, 24, and 25 but at the rear end, and are also adjustable about a horizontal transverse axis for the same purpose as the forward wings. These forward and rear wings coöperate with each other in 35 controlling the elevation and descent of the craft and its stability. All these wings, as appears from Fig. 3, are located at or near the plane of the lower edge of the superstructure. The additional rear wing 29 is 40 mounted on the top of the superstructure on the hump 20°, producing with the wings 26 and 27 the effect of a biplane at this portion of the ship. Said wing 29 is also pivoted so as to turn about a horizontal transverse axis 45 and is connected to the wings 26 and 27 so that it is oscillated about such axis when the other wings are oscillated. The wings above described, together with the elevator or hood 22, which will presently be further described, 50 furnish the vertical guiding means for the ship. The horizontal guiding means consist of the forward and rear rudders 21 and 31 which are pivotally mounted on vertical axes at the forward and rear ends of the superstructure. Reference is made to Figs. 7, 8, and 9 for a showing in detail of a mode of 55 mounting the forward rudder. Said rudder has bearing members 32 and 33 in line with one another which are mounted on a suitable portion of the framing. Preferably the 60 two rudders are operated in unison with cumulative effect in changing the direction of flight horizontally, but they may be turned in unison oppositely to one another, and it 65 is also within my contemplation to operate

them independently, and either in the same or opposite directions in order to give flexibility of control.

The hood or forward elevator 22 is carried by the forward rudder and is attached thereto by means of a horizontal pivot 34 so that its inclination may be altered at will. As this hood swings laterally with the rudder, it evidently has capacity for adjustments in two directions at the same time. 75 Its forward edge extends upward and forward from the front end of the superstructure, while its rear end passes into the superstructure, and the rudder extends to such a height and the hood is of such contour that the inner surface of the hood is as nearly as possible a continuation of the inner surface of the superstructure, there being only enough play provided vertically and horizontally to permit the appointed movement 80 of the hood.

While I do not restrict myself in the matter of controlling means for the wings, rudders, and hood, I have shown one possible form of control for the forward rudder and 90 hood in Figs. 7 to 14. The rudder controls consist of lines 35 and 36 on each side of the rudder connected to the same in front and rear, respectively, of the axis thereof, and passing over guide pulleys 37 and 38 at the opposite edges of the forward end of the superstructure. These lines are connected with operating lines 39 and 40 which pass along the edge of the superstructure to the control lever situated at any convenient point on the hull. For controlling the hood there are provided lines 41 and 42 connected to the opposite sides of the hood and passing around pulleys 43 and 44, near the axis 95 of the rudder, to the operating levers.

The boat or body which supports the ship on the ground and in the water and also provides the mounting for the motors, comprises two hulls 45 and 46 located forward and aft, respectively, and a connecting 100 bridge 47. These hulls only are designed to enter the water when the ship floats and are designed with buoyancy sufficient to float the ship with a draft approximately of eighteen inches. The water line, when the ship rests in the water is indicated by the lines *a*—*b* and *c*—*d*. This hull structure is connected to the superstructure by struts and braces indicated at 47 and 48 in Fig. 3, which may be of any character and design suitable 110 to furnish sufficient rigidity and strength. The boat construction may be modified, if desired, in order to secure greater buoyancy, or to reduce weight. For instance, the bridge 47, which is shown in Fig. 2 as narrower than the hulls and in Fig. 3 as raised above the water, may be made wider for greater deck room, or made lower to dip into the water for greater buoyancy, without 115 departure from the invention.

When the ship rests on the ground it is supported by wheels 49 and 50 located beneath the hulls. There are four wheels in all, two forward and two aft, and the forward wheels are mounted to turn laterally for guiding the craft when being propelled over the ground, and the rear wheels may be fixed in position, so far as lateral turning is concerned. Each wheel is mounted in a fork on the lower end of a tubular shaft, such shaft being contained in a hollow cylinder and bearing against a spring which absorbs the shock when the wheels strike the ground in the descent of the machine.

Additional stability while at rest is furnished by pontoons 51 and when on the ground by skids 52, shown in Figs. 15 and 16. The pontoons are hung from the opposite lower edges of the superstructure about amidship, by frames 53 which are pivoted to the superstructure. As here shown there are four pontoons, two at each side, but there may be as many additional ones as desired or required, according to circumstances. These pontoons are adapted to be swung up out of the way when not required for use, as indicated by dotted lines in Fig. 16, being operated by toggle mechanism consisting of a link 54 connected to the hanger of the pontoon, and a link 55 pivoted to the link 54 and also to the side of the bridge 47, and adapted to be operated from the bridge. 56 and 57 represent lines which are connected to the knuckles of the toggle operating mechanism for the two pontoons, respectively, and may be used to raise and lower the pontoons. The skid 52 is bow shaped and is connected at its opposite ends to the pontoon hanger, thereby serving the purpose of protecting the pontoon as well as that of a skid for bracing the machine on the ground. It may be swung about the line of its pivots into a raised position above the pontoon, as indicated by dotted lines in Fig. 15 and by the dotted arc 58 in Fig. 16, such arc representing the path in which it is thus swung.

The design of ship here illustrated includes twelve propellers for propulsion and control. Two propellers 59 are mounted on substantially horizontal axes on the forward end of the forward hull 45 on each side of the longitudinal center of the ship. Similar propellers 60 are similarly mounted on the rear end of the after hull 46. A propeller 61 is located to turn about a horizontal longitudinally extending axis in the center of the forward contracted part of the superstructure, which part by the way, I call the "throat" of the superstructure. Four propellers 62 are provided in symmetrical arrangement midway between the middle and ends of the ship and on both sides of the superstructure and are adjustable in position so as to exert a thrust either horizontally

or vertically or at an inclination. These propellers are supported on frames 63 and are so mounted that they can be swung from the position where they rotate about a longitudinal approximately horizontal axis to a position in which their axes are vertical, or approximately so. Finally there are three propellers 64, 65, and 66 rotating on vertical axes in the longitudinal vertical central plane of the ship and located above the upper surface of the superstructure.

The functions performed and the mode of operation of the ship and its component parts will be largely obvious from the foregoing description in connection with the drawings. The action of the hood and the superstructure, however, require particular explanation. The hood, flaring as it does forwardly both vertically and laterally, has the effect of compressing the air which it cuts in forward flight. The air which is not deflected below the superstructure and is compressed by the hood passes into the throat of the superstructure and exerts a lifting effect on the superstructure by virtue of its compression. The propeller 61 which is located in the throat is operated to increase the velocity of the air passing through the throat and relieve the compression of the air to some extent, whereby it both prevents escape of some of this compressed air from under the edges of the superstructure and aids in forward propulsion. In the middle of the superstructure the air somewhat recovers its normal atmospheric pressure and its original velocity, which is equal to the pressure and velocity of the outside air and balances whatever downward pressure might be exerted by the air outside on the downward slope of the middle hump of the superstructure. The inside air then acting upon the inner surface of the rear downward slope of the superstructure exerts a renewed lifting effect on this portion of the superstructure. This air, being thus compressed is enable to exert lifting force by its reaction. The flowing air then passes into the small hump 20°, where the same expansion and compression are again effected with like effect, but to a diminished degree, and finally passes off under the tail piece 30, exerting a final lifting force upon that portion. The wings at the side of and within the superstructure exert the well understood lifting effect of aeroplanes. It will be apparent then that in addition to the aeroplane wing effect, I secure in my air ship the further lifting effects due to the forward scoop shaped hood, the upwardly inclined forward throat of the superstructure, and the large gradually rounded hump at the center and the smaller hump at the rear end.

As the tail piece 30 is directly above the rear rudder, it confines the rearwardly pass-

ing air at the point of action of the rudder. This feature, that is the location of a tail and rudder in the same vertical zone, I believe to be novel with my invention.

5 Exceptional inherent stability is secured by the formation of the superstructure and the disposition of the hull. As the superstructure has its highest point in the center and is depressed, both longitudinally and 10 laterally in all directions from this highest point, it has the effect of confining air in the manner of a parachute, while the hull, which has, comparatively speaking, no lifting force in air and also supports the motors, 15 passengers, and other concentrated weights, brings the center of gravity well below the center of upward pressure, a condition essential for inherent stability, and making overturning or even careening to a dangerous 20 extent impossible. The great length of the superstructure and the wing-spread at the extreme ends prevent pitching, and the downwardly sloped sides of the superstructure give lateral steadiness and prevent side 25 slip in the air when changing direction laterally.

The functions of the horizontally driving propellers 59 and 60 and of the vertically driving propellers 64, 65, and 66 are obvious 30 and are limited to the directions in which their axes are respectively fixed. The propellers 62, however, have variable functions, being adapted either to assist the propellers 59 and 60 in driving the ship ahead, or to assist 35 the vertically thrusting propellers in raising or lowering the ship and in retarding the descent of the ship. In addition, when placed in a plane intermediate the vertical and horizontal planes they have the effect 40 both of driving the ship ahead and of raising it. While my invention contemplates the use of all of the propellers shown and described where necessary, I do not limit the invention to a combination in which 45 all of the propellers are employed, as I may omit one or more sets of propellers or one or more of the members of any set as the requirements for special uses may dictate.

50 Any number of motors may be employed. I contemplate using five motors, of which two will be mounted on the forward hull, two on the after hull, and one in the superstructure, such motors having sufficient power 55 collectively to operate all of the propellers and each being connected to a plurality of propellers.

Without limiting my invention to any particular type of construction for the superstructure, or of materials to be used in such structure, I will say that I prefer to make the same of a rigid frame work covered with cloth, the frame work being preferably of steel tubes and wires and being 65 made in sections, the limits of which are in-

dicated by the dotted curved transverse lines in Fig. 1. The cloth covering or skin of the superstructure is made in strips, each strip lying on the inner side of one of the sections and being suitably secured thereto. The 70 hood, rudders, wings, and tail piece are also preferably made of rigid skeleton construction with surfaces of cloth securely attached to the framing on both sides thereof.

The sectional construction of the superstructure, the plurality of horizontal rudders, the multiplicity of elevating controls, including the forward hood and the forward and rear wings, and the multiplicity of driving and controlling propellers, provide, in 75 connection with the great inherent stability already mentioned, the maximum of safety, since any one of the plural parts may be destroyed or disabled without destroying the stability and control of the machine, and a 80 safe descent may be made even in case any of the parts are broken away or disabled. For example, if the forward hood is blown away, the upwardly inclined end 20^a of the superstructure may remain to accomplish 85 the functions of the hood to a sufficient extent for safety. If some of the propellers are disabled, the others which remain will furnish propulsive or lifting effect. With this aspect the propellers 63 are 90 particularly important since they can take the place of the propellers 59 and 60 or of the lifting propellers 64, 65 and 66. Further the superstructure gives sufficient lifting power 95 for safety if the wings are destroyed, or if some of the sections of the superstructure are destroyed, the remaining sections and wings may have sufficient lifting power to accomplish a safe descent. Finally the dividing of the motive power into separate 100 units, or motors, some of which are widely separated from others, greatly diminishes the chance of danger of the ship being made helpless by disablement of the motive power, particularly in time of war. Even 105 with all the motors stopped, the ship will still retain its equilibrium and settle safely by virtue of the parachute construction of its superstructure.

The terms used in the foregoing description are entirely illustrative and not used with limiting intent.

What I claim and desire to secure by Letters Patent is:

1. A flying machine embodying in its construction a superstructure relatively rigid in form having downwardly sloping sides to confine air and its upper portion being higher at a point approximately midway between its ends than at any other point, 120 extending thence on a smooth curve downward and then upward to its forward end.
2. In a flying machine, a superstructure or main supporting body having a laterally arched formation at all points between its 125 130

- forward and rear ends and having the central longitudinal element of its surface downwardly inclined from its forward edge, upwardly inclined from a point in rear of 5 its forward edge toward the middle, and downwardly inclined from a point near the middle rearwardly, the sides of said body being continued below the lowest part of said central element.
- 10 3. In a flying machine, a superstructure having a surface which is curved downwardly on both sides from its longitudinal middle line, and which is formed with a large hump in its middle portion and a 15 small hump near its rear end.
4. In a flying machine, a main supporting portion having a surface of which the middle portion extending from front to rear has a rearward and downward slope at its 20 forward end, an upward enlargement in its middle portion, a downward and rearward slope from its middle portion toward its rear end, an upward enlargement near the rear end and a downward and rearward 25 slope at the extreme rear end, its sides being bent downward and carried below all parts of said middle portion, whereby to confine flowing air under compression in contact with the under surface thereof.
- 30 5. A flying machine comprising a main supporting body adapted to support the weight of the machine by the reaction on the atmosphere during propelled flight and having downwardly bent sides to confine 35 the air therein, a scoop-shaped hood or elevator connected adjustably to the forward part of said superstructure and having outwardly extending sides arranged to confine and conduct air to the under side of the 40 superstructure and between the downwardly bent sides thereof, and a tail piece rigidly secured to the rear end of the superstructure.
6. In a flying machine, a superstructure 45 consisting of a supporting surface having its opposite sides carried downwardly from its longitudinal central portion, said sides at the forward end being brought nearer together than at the central portion to form 50 a contracted throat, and a scoop-shaped hood projecting from the forward end of said superstructure and arranged to direct a current of air during propelled flight into said throat.
- 55 7. In a flying machine, a superstructure having its under surface designed to act on the air, said surface being concave with downwardly bent sides and also being imperforate so as to confine a body of air and 60 the sides of such surface converging toward the forward end to form a contracted throat, and a longitudinally thrusting propeller located in the said contracted throat wholly beneath the highest part thereof.
- 65 8. In a flying machine, a superstructure provided with a supporting surface concave on its under side, and a scoop-like member in front of said superstructure formed with downwardly bent sides converging toward the rear and projecting under the forward 70 end of the superstructure, whereby to compress and deliver air into the space within the superstructure.
9. In a flying machine, a superstructure or main supporting portion formed with an inner surface adapted to receive air pressure, the opposite edge portions of which are curved downwardly, said superstructure being formed with a contracted forward end and a contracted rear end and its central portion having an undulating outline from front to rear.
10. In a flying machine, the combination with a superstructure having an air reacting under surface, and a scoop-shaped control member mounted in front of said superstructure with its rear end extending under the forward end of the superstructure, said scoop-shaped control member being oscillatable vertically and horizontally and being formed to compress and direct a current of air under the superstructure during 80 propelled flight.
11. In a flying machine, a main supporting superstructure, a forward laterally oscillating rudder mounted on a vertical pivot below the center of the forward end of said superstructure, and a laterally spreading control member pivoted on said rudder to turn about a horizontal axis transverse 90 to the direction of propelled flight.
12. In a flying machine, the combination with a superstructure having an air reacting surface, the sides of which are carried downwardly to form a longitudinal channel, and a hood projecting forwardly and upwardly from the forward end of said superstructure to a point higher than the said forward end, and extending at its rear within the forward end of such channel.
13. In a flying machine, the combination with a superstructure having an air reacting surface, the sides of which are carried downwardly to form a longitudinal channel, and a hood projecting forwardly and upwardly from the forward end of said superstructure and extending at its rear within the forward end of such channel, said hood being mounted to swing laterally 105 about a vertical pivot.
14. In a flying machine, the combination with a main supporting aeroplane structure of an oscillatable rudder at the forward end of said structure and a vertically oscillatable hood carried by said rudder and 110 extending forwardly and flaring laterally from the forward end of said superstructure.
15. In a flying machine, the combination with a main supporting aeroplane structure 115

of an oscillatable rudder at the forward end of said structure and a vertically oscillatable hood extending forwardly and flaring laterally at both sides from the forward 5 end of said superstructure, said hood being carried by the rudder and having its rear end extending under the forward end of the superstructure.

16. In a flying machine, the combination 10 with a main aeroplane structure having its opposite side edges depressed to form a channel for air and the forward ends of said side edges being converged to form a contracted throat, a forwardly flaring hood 15 mounted in the throat of said superstructure and arranged to direct a current of air into such throat, and a rearwardly thrusting propeller located in said throat.

17. A flying machine comprising an aeroplane superstructure of greater length than width having its sides carried downward to provide a channel open at both ends to permit free ingress and egress of air, wings laterally extending to opposite sides from the 25 highest part of the rear end of said superstructure, and wings beneath the aforesaid wings at approximately the level of the side edges of this part of the superstructure.

18. A flying machine comprising an aeroplane superstructure of greater length than width having its sides carried downward to provide a channel open at both ends to permit free ingress and egress of air, wings laterally extending to opposite sides from the 35 highest part of the rear end of said superstructure, wings beneath the aforesaid wings at approximately the level of the side edges of this part of the superstructure and wings extending laterally from the forward 40 end of the superstructure at the level of the side edges at said forward end.

19. In a flying machine, the combination 45 with a main aeroplane structure having greater length than width and having its opposite side edges bent downwardly, a laterally and vertically oscillatable hood mounted at the forward end of said superstructure, and upper and lower wings projecting oppositely from the sides of said 50 superstructure at its rear end.

20. In a flying machine, a superstructure of rigid construction having its under surface of concaved formation and exposed to

the action of the air through which the machine travels, such under surface having an 55 upward enlargement in the central portion and a smaller upward enlargement adjacent to the rear end, and a guiding plane extending across the top of such rear enlargement.

21. In a flying machine, the combination 60 with a rigid superstructure having its opposite side edges curved downwardly, a plane extending across and to each side of the middle part of said superstructure adjacent to the rear end thereof, and wings 65 extending laterally from the edges of the superstructure partly beneath and partly forward of said plane.

22. In a flying machine, the combination 70 with a transversely bowed aeroplane structure of an upper transverse plane and lower wings extending laterally from respectively the mid portion and the edges of said superstructure.

23. In a flying machine, the combination 75 with a transversely bowed aeroplane structure of an upper plane and lower wings extending laterally from respectively the mid portion and the edges of said superstructure, said wings being oscillatable 80 about transverse horizontal axes.

24. In a flying machine, the combination 85 with a transversely bowed aeroplane structure of an upper plane and lower wings extending laterally from respectively the mid portion and the edges of said superstructure, said wings being oscillatable about transverse horizontal axes, and being connected to oscillate in unison.

25. In a flying machine, the combination 90 with a main aeroplane superstructure of a forward rudder adjacent to the forward end of said superstructure, a rear rudder adjacent to the rear end of said superstructure, a scoop shaped member connected to 95 the upper edge of the forward rudder and a rigid tail piece connected to the rear end of the superstructure and extending over the rear rudder.

In testimony whereof I have affixed my 100 signature in presence of two witnesses.

CHARLES E. GORDON.
